DISPENSING DEVICE

Otto Goetz, Batavia, N. Y., assignor to R. E. Chapin Manufacturing Works, Inc., Batavia, N. Y., a corporation of New York

Application July 2, 1936, Serial No. 88,624

6 Claims. (Cl. 221—77)

This invention relates to a compressed-air sprayer of the tank type, adapted to be carried about by the user during the act of spraying trees, shrubs, flowers, and other plants, or it may be used for spraying whitewash, cold water paint, oil, or other liquid substances for various purposes.

Devices of this kind are designed to contain spraying liquids, and by means of a pump, usually arranged axially in the tank, cause the liquid to be ejected under considerable pressure. The tanks of such devices usually have a closure from which the pump is suspended, and in order to refill the tank with spraying liquid, such closure must be removed from the filling opening, but due to the internal pressure applied to the closure by the compressed-air within the tank, difficulty is experienced in opening the closure, or even in loosening the same so as to allow the air under pressure to gradually escape with a view of more readily removing the closure from the tank to permit of refilling the latter. Moreover, spraying devices of this kind have comparatively small filling openings.

One of the objects of my invention is to provide a closure which will permit the pressure within the tank to be quickly and easily relieved, and also to provide a comparatively large filling opening, fully covered by the closure, so that the tank can be more easily supplied with the spraying liquid than has heretofore been possible, and at the same time give assurance that the closure will be subjected to equal pressure around its entire circumference.

Other objects of my invention are the application of maximum leverage to the closure by means of a screw-threaded element capable of applying a powerful wedge-force to the axial region of the cover, so that the latter will be sealed with equal pressure around the filling opening and effectively guard against leakage of air-pressure from the interior of the tank, yet permit the cover to be easily loosened to allow the air-pressure within the tank to escape, and thus assist in the more ready removal of the closure from the tank for the purpose of conveniently refilling the same.

With the above and other objects to appear hereinafter, my invention consists in the combination and arrangement of parts, and in the novel features of construction to be hereinafter described and more particularly pointed out in the subjoined claims.

In the drawings,

Fig. 1 is a side elevation of a liquid-spraying tank equipped with my invention.

Fig. 2 is an enlarged vertical section through

the upper portion thereof taken on line 2—2, Fig. 1.

Fig. 3 is a top plan view of the tank reduced in size from that shown in Fig. 2.

Fig. 4 is a reduced transverse section taken on line 4—4, Fig. 2.

Fig. 5 is a transverse section taken on line 5—5, Fig. 2.

Fig. 6 is a transverse section taken on line 6—6, Fig. 2.

Fig. 7 is an enlarged vertical section taken through the filling funnel of the tank on line 7—7, Fig. 3, the yoke bar and the closure being omitted.

Fig. 8 is an enlarged section taken on line 8—8, Fig. 3, looking in the direction of the arrow crossing said line.

The tank includes a body portion 10 having a rounded shoulder wall 11 to which is secured the filling funnel 12 of the device. The filling funnel is of somewhat smaller diameter than the body portion of the tank, and its peripheral wall 13 is curved outwardly and downwardly at its upper end, as at 14, to stiffen the same and give it a finished appearance; also to more conveniently permit the tank to be emptied. At the lower end of this peripheral wall 13, a comparatively wide inwardly-directed flange 15 is formed, around the inner portion of which is bent the sheet-material forming the shoulder wall 11, as at 16; the rebent or recurred portion directed over the flange 15 determining the diameter of the filling opening, designated by the numeral 17, and serving also as a seat for the closure 18. This construction enables the funnel to be made quite large in diameter and thus saves time in filling the tank, and at the same time making it more convenient to fill as well as to drain or empty the tank. The filling funnel is therefore considerably larger than the filling opening and can, if desired, be made still larger without varying the size of the filling opening. It has been found to be of advantage to reduce the diameter of the filling opening for certain types of spraying tanks without reducing the diameter of the filling funnel, but in all instances the filling funnel will be measurably larger than the filling opening. Such variations are permissible only by reason of the particular construction defined.

The closure 18 is of circular formation, bent or otherwise fashioned at its marginal portion to provide a downwardly-facing groove or washer-seat 19 directly over the recurred portion of the shoulder wall 11. This washer-seat, which is of channel formation and circular in contour, has a washer 20 entered therein which is designed to

50 provide a downwardly-facing groove or washer-seat 19 directly over the recurred portion of the shoulder wall 11. This washer-seat, which is of channel formation and circular in contour, has a washer 20 entered therein which is designed to

bear against the recurved portion of the shoulder wall. The closure closes downwardly and is provided centrally with an upstanding boss 21; and as this closure is constructed of heavy sheet-material, both the washer and the said upstanding boss are stamped therein. The boss 21 is therefore hollow and provided with internal screw-threads 22.

The pump employed in this tank is similar to those commonly used in tanks of this kind, and the upper end thereof only is illustrated. It comprises a pump cylinder 23 having a flanged externally-threaded collar 24 surrounding its upper end and it is welded or otherwise secured thereto in any approved manner and designed to have its threads engage the internal screw-threads 22 of the central boss 21 on the closure. In this manner the pump is axially suspended from the closure and is removable therewith.

Bearing against the upper face of the boss 21 is a power or clamping screw 25 which is provided with a screw-threaded bore 26 extending upwardly thereinto from the lower end thereof. This bore is adapted to receive a packing nut 27 between which and the inner end of said bore 26, packing 28 is compressed. This packing nut is enlarged along its lower portion to form an upwardly-facing shoulder 29, which bears against a washer 30 disposed between said shoulder and the underside of the power or clamping screw 25 while retained within a central opening 31 in the upper wall of the boss 24. At its lower end the enlargement of said packing nut is provided with an outstanding flange 32 between which and the top wall of the boss 21 a spiral expansion spring 33 is disposed, said spring surrounding the enlargement of the packing nut and being designed to maintain the power or clamping screw 25 yieldingly in contact with the closure 18, or more particularly the upper surface of the boss 21 on said closure.

From the foregoing it will be apparent that the pump cylinder 28 depends from the closure 18, and by reason of the yielding connection between the closure 18 and the power or clamping screw 25, said device is also maintained at all times in assembled relation with said closure.

Stamped into the peripheral wall of the filling funnel 12 from the inner side and at diametrically opposite points thereof are lock notches or depressions 34, the stamping of the same providing projecting portions on the exterior of said peripheral wall. Each of these notches or depressions comprises three parts; one an entrance portion 35 which opens at the upper edge of said peripheral wall and leads to a circumferentially-trending lock portion 36 through the medium of a pass portion 37, and by reason of the fact that the lock portion 36 is of greater height than the pass portion 37, a lug 39 is created under the stamping so provided, for a purpose to appear hereinafter.

A lock element in the form of a yoke-bar 40 is screw-threadingly connected with the power or clamping screw 25, and it is preferably constructed of heavy sheet material stamped to form a central boss 41 which is internally screw-threaded to receive the external screw-threads of said power or clamping screw. Said lock element or yoke-bar extends diametrically over the closure 18 and is of a length somewhat greater than the internal diameter of the filling funnel 12 so as to permit its ends to be entered in the entrance portions 35 of the notches or depressions 34. These ends are entered into said notches by movement in the di-

rection of the arrow 42 in Fig. 8, and as they reach the bottom walls of said entrance portions, said yoke-bar is given rotative movement to cause the ends thereof to move through the pass portions 37, in the direction of the arrow 43 in Fig. 3. When these ends have passed through the pass portions 37, they will have reached the lower ends of the lock portions 36. The power or clamping screw 25 will then be rotated in a given direction to cause the yoke-bar to move upwardly in the direction of the arrow 44 in Fig. 8. This upward movement will result in opposite ends of the yoke-bar engaging behind the lugs 39, and as said power or clamping screw is tightened, the ends or terminals of said yoke-bar will be firmly pressed against the upper or overhanging surfaces of the lock portions 36, with the result that screw or wedge-like pressure will be applied centrally to the closure 18 to force the same downwardly at its marginal portion against the recurved portion 16 of the shoulder wall, and due to the tremendous leverage applied to said closure by means of said power or clamping screw, the washer 28 will be subjected to equal pressure throughout its circumference, thereby preventing leakage of air from within the tank. The direction of rotation of said power or clamping screw depends on the direction of the screw-threads formed thereon, and while I have in the drawings shown the direction of rotation to be counter-clockwise, such action will preferably be reversed. A reverse rotative movement of the power or clamping screw will result in the loosening of the lock element or yoke-bar so that gradual exhausting of the pressure from within the tank can take place, and as the tank is gradually being relieved of pressure, the complete disconnection of said yoke-bar from the peripheral wall of the filling funnel can be easily made, with the result that the yoke-bar, cover, and pump, as well as the power or clamping screw, can be conveniently lifted from the tank as a unit so as to leave the large filling opening 17 provided in the top of the tank entirely unobstructed.

To permit of the ready manipulation of the power or clamping screw, the upper end of the latter is enlarged and made hollow so as to provide an internal overhanging flange 45, which is provided with a notch 46 for a purpose to presently appear. Slidably arranged within the power or clamping screw 25 and within the packing nut 22 is the piston-rod 47 of the pump, or the pump-rod as it may be termed, the lower end of which is provided with a suitable disk or other piston or plunger slidable within the pump cylinder 23, in the same manner as provided for in pressure pumps now in use in spraying tanks. This pump-rod is reduced in diameter at its upper end to form an upwardly-facing shoulder 48, and on this reduced end is pinned or otherwise secured a handle 49, provided with a hub or cylindrical portion 50 passed through the central opening 51 formed by the flange 45 in the hollow upper end or head of said power or clamping screw. Projecting laterally from the hub or cylindrical portion of said handle is a stop-lug 52 which is designed to engage an inwardly-projecting stop 53 extending inwardly from the peripheral wall of said hollow portion or head. Upon rotating the handle 49 and the piston rod 47 until the stop-lug 52 on said handle is brought in line with the notch 46, the reciprocation of the piston rod is permitted for the purpose of subjecting the liquid within the tank to the desired pressure. After the pressure

is built up to the desired degree, the handle again may be moved rotatively to bring the stop-lug 52 thereon in line with said notch 46 and allow said lug to enter the hollow portion or head of the power or clamping screw; and upon then turning the handle, said stop-lug will engage either one or the other side of the stop 53. When the stop-lug 52 is in either of the two last-mentioned positions, or in any other position not in direct alinement with the notch 46, the pump rod and its piston or plunger will be locked in its lowered position, due to the fact that the inwardly-directed flange 45 on the hollow head of said power or clamping screw will prevent upward movement of the piston or pump-rod, and movement in a downward direction will naturally be prevented by the bottom wall of said hollow head.

Assuming the parts to be as shown in Figs. 1 and 2, and the power or clamping screw to be provided with a left-hand screw-thread, as shown, the piston or plunger of the pump will be in its lowered position with the handle locked to the power or clamping screw, the yoke-bar 40 in firm contact with the upper walls of the lock portions 36 of the notches or depressions 34, and the closure 18 firmly seated to seal the filling opening 17. In order to release pressure on the closure 18, the handle 49 will have to be rotated clockwise to bring the stop-lug 52 from the position shown in dotted lines in Fig. 6, or from any other position it may be in, to that shown in full lines in said figure. Slight additional pressure then applied to the handle in a rotative direction clockwise will result in the act of unscrewing the power or clamping screw 25 within the lock element or yoke-bar 40 and due to said power or clamping screw being held in firm contact with the cover through the medium of the spiral spring 33, easement of the ends of the lock element or yoke-bar will take place, which permits a corresponding easement of the washer 20 around the marginal portion of the closure from the tank structure, which it is to be understood includes the filling funnel 12. Consequently, pressure from the interior of the tank will be relieved so that a free rotative movement is provided for the handle and the power or clamping screw, and an unstrained lowering of the lock element or yoke-bar assured. During such operation, the air within the tank is released and the closure is completely relieved of internal pressure.

When the ends of the lock element or yoke-bar are lowered to the common lower wall of the three portions 35, 36 and 37 of the depressions or notches 34, said ends may be moved through the pass portions 37 so as to enter the entrance portions 35 and thus permit the free removal of said lock element or yoke-bar from the tank, and with it, the connected parts including the complete pump with its handle, the power or clamping screw, and the closure. Removal of these parts from the tank leaves the filling funnel unobstructed and presents a comparatively large filling opening so that the spraying or other liquid can be easily poured into the tank and the level of the liquid determined at all times during the act of refilling the tank. When the tank is refilled, the assemblage comprising the pump parts, power or clamping screw, lock element or yoke-bar, and closure may then be placed on the tank by a mere reversal of the operative parts from that required for removing the cover; it simply being necessary to reverse the rotative movement of the leverage screw-device after entering the ends of the yoke-bar in the lock portions 36 of the depressions or

notches 34 by passing said ends through the entrance portions 35 and pass portions 37. When so reversing the movement, the stop-lug 52 on the hub of the handle 49 will engage the stop 53 in the hollow head of the power or clamping screw, as shown in dotted lines in Fig. 6, and thus cause tightening of said screw within the lock element or yoke-bar when rotating the handle 49 in a counter-clockwise direction. Obviously, the more pressure exerted on the leverage screw-device by means of the handle 49, the more powerful will be the pressure exerted by the ends of the yoke-bars against the upper walls of the lock portions 36, and the downward pressure around the marginal portion of the closure 18 will be distributed evenly and will be in accordance with the pressure applied to the ends of the lock element or yoke-bar.

The peripheral wall 13 of the filling funnel 12 while serving as a means to guide and lock the terminals of the lock element or yoke-bar 40, includes the two diametrically opposite notched portions which serve as stirrups, and it will therefore be apparent that such stirrups, or anchor-elements as they may be termed, need not necessarily be embodied in a peripheral or circular wall, since they may rise separately from the tank and serve the same purpose. Consequently the invention is capable of use with or without the employment of a filling funnel. It will also be apparent that when using a filling funnel, the filling opening of the tank will necessarily be restricted in size to a diameter smaller than that of the peripheral wall of said filling funnel, whereas if the stirrups or anchor-elements are independently used at diametrically opposite points without resorting to the use of a peripheral or circumferential wall serving as a filling funnel, such stirrups or anchor-elements may be spaced apart a greater distance and may even be separated a distance greater than the diameter of the tank, so that the filling opening could be as large in diameter as the internal diameter of the tank, or approximately so.

It may here be stated that, like all compressed-air sprayers of this type, a flexible hose or similar conduit 54 is connected to the upper end of the tank and opens into it, and it is provided with a spraying-nozzle and suitable means for shutting-off and regulating the spraying of the liquid directed therethrough. This hose or conduit is therefore under manual control, and when opening the same to the flow of the spraying material, the pressure within the tank will cause the liquid to be passed thereinto and sprayed from the nozzle.

I also provide the tank with a shoulder strap 55, such as usually employed in sprayers of this type, so as to enable the device to be conveniently carried about.

Having thus described my invention, what I claim is:

1. A compressed-air spraying tank having an inwardly-directed shoulder wall provided with a comparatively large opening and having the metal at said opening rebent, a comparatively large filling funnel of somewhat smaller diameter than said tank and of larger diameter than said opening applied to the top of said shoulder wall and including a comparatively wide inwardly-directed flange at its lower end over the inner portion of which the rebent portion of said shoulder wall is laid, said filling funnel including a peripheral wall having internal lock-notches, a closure for said opening including a washer in contact with the

reentrant portion of said shoulder wall, a lock-element extending diametrically over said closure and having opposite ends thereof detachably engaged in said lock-notches, and a power-device movably engaging said lock-element and closure to exert pressure against the two in opposite directions, said power-device being yieldingly secured to said closure.

2. A compressed-air spraying tank having an inwardly-directed shoulder wall provided with a comparatively large central opening and having the metal at said opening reentrant, a comparatively large filling funnel applied to the top of said shoulder wall and including a comparatively wide inwardly-directed flange at its lower end over the inner portion of which the reentrant portion of said shoulder wall is laid, said funnel being of a diameter somewhat larger than that of said opening and somewhat smaller than that of said tank, said filling funnel including a peripheral wall having internal notches, a closure for said opening including a washer in contact with the reentrant portion of said shoulder wall, a lock-element extending diametrically over said closure and having opposite ends thereof detachably engaged in said lock-notches, an externally-threaded device threadingly engaging said lock-element midway between its ends and in yielding contact with the central portion of said closure at its lower end, and means to rotate said externally-threaded device clockwise or counter-clockwise.

3. A compressed-air spraying tank having an opening centrally in its top, and a closure structure removable as a unit from said tank and comprising a closure placed over said opening to close the same, a lock-element disposed above said closure detachably locked to said tank, a screw power-device threaded into said lock-element and bearing centrally against said closure, a nut extending through said closure from the inner side thereof and threaded into said screw-power device, said nut having a flange at its lower end, and a spiral-spring surrounding said nut and bearing at one end against said flange and at its other end against the under side of said closure.

4. A compressed-air spraying tank having an opening centrally in its top, a closure having a hollow upstanding central boss internally screw-threaded and having also a central opening in the upper wall of said boss, a pump having a cylinder depending from said closure and threaded into said boss and a pump-rod reciprocal in said cylinder, a screw power-device bearing against the upper surface of said boss around the opening therein, a nut entered into said screw power-device from the bottom thereof and extending into said cylinder, said nut having an

outstanding flange at its lower end, a spiral-spring surrounding said nut between the top wall of said boss and said flange and serving to hold said screw power-device yieldingly in contact with said boss, said pump rod passing through said nut and screw power-device and having a handle at its outer end, and means connected to said tank into which said screw power-device is threaded so as to cause pressure to be exerted centrally on said closure upon rotating said screw power-device in a given direction.

5. A compressed-air spraying tank having an opening centrally in its top, a closure having a hollow upstanding central boss internally screw-threaded and having also a central opening in the upper wall of said boss, a pump having a cylinder threaded into said boss and depending therefrom, a screw power-device bearing against the upper surface of said boss around the opening therein, a nut having its upper portion reduced to form an upwardly-facing shoulder and having said upper reduced portion threaded into said screw power-device from the bottom, a washer within the opening of said boss between said screw power-device and said upwardly-facing shoulder, said nut having a projecting portion at its lower end, a spiral spring between said projecting portion and the top wall of said boss, and a pump-rod extending through said nut and screw power-device and having a handle at its outer end to actuate said pump rod.

6. In a compressed air spraying tank having an opening centrally in its top, a combined closure structure and pump removable as a unit from said tank and comprising a closure placed over said opening to close the same, a lock element disposed above said closure detachably locked to said tank, a screw power-device threaded into said lock element and bearing centrally against said closure, a nut extending through said closure from the inner side thereof and threaded into said screw power-device, said nut bears, said packing nut having a flange at its lower end, a spiral spring surrounding said nut and bearing at one end against said flange and at its other end against the under side of said closure, a pump depending centrally from said closure and having a pump rod extending upwardly through said nut and said screw power-device and having a handle at its outer end to actuate said pump rod and means for interlocking said handle with said screw power-device to prevent actuation of said pump rod and to cause actuation of said screw power-device upon rotation of said handle and to disengage said handle from said screw power-device to allow actuation of said pump-rod.
